SOUND-PRODUCING AND SOUND-REPRODUCING APPARATUS

Edward W. Kellogg, Moorestown, N. J., assignor to
Radio Corporation of America, a corporation
of Delaware

Application March 1, 1941, Serial No. 381,220

9 Claims. (Cl. 181—31)

This invention relates to combined sound-producing and sound-reproducing apparatus, and more particularly to the sound-distribution system of a combined electric piano and radio receiver and/or electric phonograph.

In a conventional electric piano with which is incorporated a radio receiver or electric phonograph, it is customary to mount the loudspeaker on the sounding board which acts as a coupled resonator, or else in the panel under the keyboard. In such an arrangement, the sound does not come directly to the ears of the person playing the piano, and some reverberation effect is present. Even with this loudspeaker arrangement, however, electric pianos have been criticised for the sudden "attack" of the tone, that is, the sharpness with which the notes begin. Another objection to conventional electric pianos of this type is that feedback troubles are encountered by reason of the fact that the loudspeaker cones are usually mounted close to the strings.

While the location of the sound source near the floor is not objectionable for piano music, this is by no means the most favorable location for a loudspeaker for radio reception. It is very desirable for radio reception that the loudspeaker be near the level of the listener's ears and that it shall radiate horizontally in order that the high frequency components of sound may not be lost and the clarity of diction thereby sacrificed. On the other hand, locating the loudspeaker in the upper part of the piano cabinet and directed horizontally would be most objectionable to the person playing the piano, who has little choice of position. It would be entirely too close for pleasure since the piano music sound would reach the pianist's ears with no reverberation, and with an even worse sharp attack than with the loudspeaker located close to the floor.

The primary object of my present invention is to provide an improved combination electric piano and sound-reproducing apparatus which will be free from the foregoing objections, and wherein the most desirable listening conditions are produced for both piano music and for radio reception or phonograph reproduction.

More particularly, it is an object of my present invention to provide, in a combined electric piano and sound-reproducing apparatus, a novel sound-distribution system for the loudspeaker thereof whereby the sudden "attack" of the tone will be less conspicuous and wherein the tendency to feedback is greatly minimized.

Another object of my present invention is to provide an improved combination electric piano

and sound-reproducing apparatus which may be readily conditioned for suitably directing the sound waves emanating from the loudspeaker thereof in accordance with whether the piano is to be actuated to produce sounds locally, or whether the sound-reproducing apparatus is to be actuated to reproduce sounds originating in a radio receiver or phonograph.

It is a further object of my invention to provide a loudspeaker for use in a combination piano and radio receiver which will radiate the high frequency sounds approximately horizontally from a source several feet from the floor when the instrument is in use for radio reception, but will direct the high frequency sounds away from the pianist and not directly toward any listeners when the loudspeaker is serving to radiate the piano music.

Still another object of my present invention is to provide an improved combination electric piano and sound-reproducing apparatus as aforesaid which can be readily manipulated to produce the desired effects.

It is also an object of my present invention to provide an improved combination electric piano and sound-reproducing apparatus as aforesaid which is relatively simple in construction and highly efficient in use.

According to my present invention, instead of mounting the loudspeaker cone in the panel below the keyboard of the piano, I preferably employ a somewhat smaller than conventional cone and mount it above the keyboard in a manner such that the higher frequencies are radiated from the front of the cone, while the back of the cone is connected to a suitable horn adapted to reproduce particularly the lower frequencies.

Such a sound radiating system is, in principle, in accordance with that described in U. S. Patent to Olson No. 2,224,919. In this speaker, the front of the cone is freely exposed as in the usual baffle type of radio loudspeakers, while the horn structure which is coupled to the back of the cone or diaphragm serves to improve the radiation of low frequency tones. The horn may be so constructed as to act as a low-pass acoustic filter. It serves to increase the radiation of low frequency sounds and to improve the efficiency of the loudspeaker. By confining the low frequency waves within the horn passages, the horn also reduces the likelihood of transmitting vibrations to the piano strings and thus producing a feedback effect when the loudspeaker is serving to produce piano music.

Preferably, the cone is arranged to face the

front of the piano cabinet to radiate sound through an opening in the front wall thereof. An opening is also provided in the top wall of the cabinet and enough space is provided between the cone and the front cabinet wall to pivotally accommodate a reflector. This reflector is so connected with the keyboard cover that, when the cover is down over the keys, the reflector occupies a horizontal position external to the path between the loudspeaker cone and the front wall opening, a hinged cover then closing the top wall opening, so that sounds radiated by the loudspeaker pass out directly through the front wall opening to the exterior of the cabinet. On the other hand, when the keyboard cover is raised to expose the piano keys, the reflector is raised to an inclined position in front of the loudspeaker cone for the purpose of deflecting the sounds radiated thereby in an upward direction through the opening in the top of the piano cabinet, the cover in the top wall being then in raised position. The reflecting surface of the reflector is not necessarily flat, but may be designed to scatter the sound. The result will be that the higher frequency components of the sound will be heard only after some reflection from the room ceiling and walls, thus adding a reverberation effect as compared with listening to sounds radiated directly by the cone.

When the instrument is in use for radio reception or phonograph reproduction, the keyboard cover is closed and the reflector is in its lower position, so that the listener will have the benefit of direct sound from the loudspeaker, as is generally preferred for speech. On the other hand, when the piano is being played, the keyboard cover is, of necessity, open, the reflector is in its raised position, and the sounds emanating from the loudspeaker are directed upwardly through the top wall opening. Of course, the listener may also cause the sounds emanating from the loudspeaker to pass up toward the ceiling when the radio or phonograph is reproducing music, if he prefers, so as to enjoy the benefit of indirect sound, by simply raising the keyboard cover.

The novel features that I consider characteristic of my invention are set forth with particularity in the appended claims. The invention itself, however, both as to its organization and method of operation, as well as additional objects and advantages thereof, will best be understood from the following description of one embodiment thereof, when read in connection with the accompanying drawing, in which

Figure 1 is a transverse sectional view of a combined electric piano and radio receiver according to my present invention and arranged to direct the sound waves upwardly toward the ceiling, and

Figure 2 is a similar view, but showing the parts arranged so as to direct the sound forwardly.

Referring more particularly to the drawing, wherein similar reference characters indicate corresponding parts throughout, there is shown a piano casing 1 having a front wall 3 provided with an opening 5 which may be covered by a suitable grille 7 in conventional manner. The cabinet 1 also includes a top wall 9 having an opening 11 therein which may be covered by a suitable grille 13. The top wall 9 also has pivotally connected thereto a cover 15 which is adapted to close the opening 11 when in lowered position and to expose the opening 11 when in

raised position. Pivotally mounted on the front wall 3 is a keyboard cover 17 which, in lowered position, covers the piano keys 18, as clearly shown in Fig. 2, the keys 18 being exposed for actuation by the player when the keyboard 17 is raised to the open position shown in Fig. 1.

Within the cabinet 1, and preferably above the sounding board (not shown), is a cone loudspeaker 19 having a conical diaphragm 21 which faces forwardly toward the front wall opening 5, a reflector 23 being pivotally mounted in the casing or cabinet 1 between the cone 21 and the front wall 3. The cabinet 1 also houses a suitable sound-reproducing apparatus, such as a radio receiver 25 having one or more control knobs 27 on the front wall 3, or an electric phonograph, the loudspeaker 19 being operatively associated with both the electric piano and the sound-reproducing apparatus.

Pivotally connected at one end to the reflector 23 and at its other end to a bracket 29 which is secured to the cover 15 is a link member 33 which is so coupled to the cover 15 and the reflector 23 that they may move in unison to and from the two positions shown in Figs. 1 and 2. The keyboard cover 17 has secured thereto a lever 35 which is coupled to a lever 37, secured to the reflector 23, by a link 39. The link mechanism 35, 37, 39 is so related to the keyboard 17 and the reflector 23 that, when the keyboard cover 17 is lowered to the position shown in Fig. 2 in order to cover the keys 18, the reflector 23 will be lowered to its horizontal position external to the path between the loudspeaker cone 21 and the front wall opening 5, the link 33 at the same time pulling the cover 15 down into closed position over the opening 11. Sound waves radiated by the loudspeaker 21 can then pass out of the cabinet 1 only forwardly through the front wall opening 5. On the other hand, when the keyboard 17 is raised to the position shown in Fig. 1, the link 39, in cooperation with the levers 35 and 37, raises the reflector 23 to the inclined position of Fig. 1 to block off the path between the cone 21 and the front wall opening 5. At the same time, the link 33 raises the cover 15 to the position shown in Fig. 1 in order to expose the opening 11, and sound waves emanated by the loudspeaker are then reflected upwardly through the opening 11 by the reflector 23.

From the foregoing description, it will be obvious that the instrument can be arranged so that the high frequency sounds radiated by the front surface of the cone 21 will pass either directly out through the front wall opening 5, or upwardly through the top wall opening 11 for subsequent reflection from the ceiling and walls of the room, thereby adding a reverberation effect as compared with listening to sounds radiated directly by the cone 21. This reverberation effect is desirable when music is being produced by playing the piano, especially in view of the unavoidable close proximity of the person playing the piano, and the instrument is automatically conditioned therefor when the piano keyboard 17 is raised. When, however, speech is being reproduced by the radio receiver or phonograph 25, and it is preferable to have the sound pass directly and without reflection and reverberation to the listener, who would then normally be sitting further away, the piano keyboard cover 17 is lowered to the position of Fig. 2, and the sounds will pass directly out through the front wall opening 5. To the back or rear sur-

face of the cone 21 is preferably coupled a long, folded horn of the type shown, for example, in the above identified Olson patent, the latter horn being particularly adapted to reproduce the low frequencies and directing the sound waves forwardly into the room through an opening 41 in the lower part of the cabinet 1. The latter horn is conveniently arranged within the cabinet 1 and is constantly coupled to the rear surface of the cone 21 regardless of the position of the reflector 23.

Although I have shown and described but one embodiment of my invention, it will be apparent to those skilled in the art that many other modifications thereof, as well as changes in the one described herein, are possible. For example, if desired, the movement of the keyboard cover 17 from one position to the other may be made to actuate a suitable switch or other mechanism for controlling the energy delivered to the loudspeaker 19 by either the electric piano or the sound reproducing device 25. Also, instead of depending entirely on a reflector to change the direction of radiation from the front of the diaphragm, the entire loudspeaker may be turned to either of two positions, provision being made to maintain suitable coupling between the back of the cone and the horn, for both positions of the speaker unit. Other similar modifications will, no doubt, readily suggest themselves to those skilled in the art. I, therefore, do not wish to be limited except insofar as is made necessary by the prior art and by the spirit of the appended claims.

I claim as my invention:

1. In an electrical sound producing instrument including a loudspeaker, a cabinet in which said loudspeaker is housed, said cabinet including a top and a front wall each of which has an opening therein through which sound waves emitted by said loudspeaker may pass to the exterior of said cabinet, a cover hingedly connected to said top wall and adapted to be swung to and from open and closed positions relative to the opening in said top wall, a reflector hingedly mounted in said cabinet and arranged for swinging movement into and out of two positions in one of which said reflector is outside of the path between said loudspeaker and the opening in said front wall and in the other of which said reflector is interposed in said path to shut off communication between said loudspeaker and said front wall opening and to direct sound waves emitted by said loudspeaker toward said top wall opening, and means interconnecting said cover and said reflector for movement in unison such that, when said cover is swung to open position relative to said top wall opening, said reflector is moved to its second-named position, and when said cover is swung into closed relation with said top wall opening, said reflector is moved to its first-named position.

2. The invention set forth in claim 1 characterized by the addition of means on said cabinet for actuating said interconnecting means whereby to move said cover and reflector into one or the other of said positions.

3. In a combined electric piano and electrical sound reproducing apparatus, the combination of a cabinet including a top and a front wall, each of said walls having an opening therein through which sound waves emanating from a source within said cabinet may pass out to the exterior of said cabinet, a loudspeaker within said cabinet operatively associated with both said

- piano and said sound reproducing apparatus and adapted to emit sound waves, and selectively operable means for causing the sound waves emitted by said loudspeaker in response to said piano 5 to pass out through the opening in said top wall and for causing the sound waves emitted by said loudspeaker in response to said sound reproducing apparatus to pass out through said other opening.
4. In a combined electric piano and electrical sound reproducing apparatus, the combination of a cabinet including a top and a front wall, each of said walls having an opening therein through which sound waves emanating from a 15 source within said cabinet may pass out to the exterior of said cabinet, a loudspeaker within said cabinet operatively associated with both said piano and said sound reproducing apparatus and adapted to emit sound waves, a cover hingedly connected to said top wall and adapted to be swung to and from open and closed positions relative to said top wall opening, a reflector hingedly mounted in said cabinet and arranged for swinging movement into and out of two positions in one of which said reflector is outside of the path between said loudspeaker and said front wall opening and in the other of which said reflector is interposed in said path to shut off communication between said loudspeaker and said front wall opening and to direct sound waves emitted by said loudspeaker toward said top wall opening, and selectively operable means for moving said cover to open position and said reflector to its second-named position when said 20 loudspeaker is to be actuated by said piano and for moving said cover to closed position and said reflector to its first-named position when said loudspeaker is to be actuated by said sound-reproducing apparatus.
5. The invention set forth in claim 4 characterized in that said piano includes a hinged key cover, characterized further by the addition of a link member pivotally connected to both said top wall cover and said reflector whereby 25 to couple said top wall cover and reflector for movement in unison, and characterized still further by the addition of link mechanism coupling said key cover and said reflector for movement in unison, said link mechanism and link member being so constructed and arranged relative to said key cover, said top wall cover and said reflector that, when said key cover is raised to expose the piano keys, said link mechanism and link member will cause said reflector to move into its second-named position and said top wall cover to open, and when said key cover is lowered to cover said keys, said link mechanism and link member will cause said reflector to move into its first-named position and said top wall cover to close.
6. The invention set forth in claim 4 characterized in that said loudspeaker includes a diaphragm, and characterized further in that said top and front wall openings are associated with only the front surface of said diaphragm.
7. The invention set forth in claim 4 characterized in that loudspeaker includes a diaphragm, characterized further in that said top and front wall openings are associated with only the front surface of said diaphragm, and characterized still further by the addition of a horn in said cabinet coupled to the rear surface of said diaphragm, said horn being constantly in coupled relation to said rear surface.
8. In a combined electric piano and electrical

sound reproducing apparatus all housed in a single cabinet, a loudspeaker located in the upper part of said cabinet and including a diaphragm, said cabinet having an opening therein in one wall thereof adjacent another part of said cabinet and said piano including a plurality of strings, means coupling the back of said diaphragm to said opening and providing an acoustic passage for conducting from said diaphragm to said opening sound waves radiated by the back of said diaphragm, said means being constructed and arranged to shield said piano strings from sound waves radiated by said diaphragm, and means for altering the direction of sound waves radiated from the front of said diaphragm.

9. In a combined electric piano and electrical

sound reproducing apparatus all housed in a single cabinet, a loudspeaker located in the upper part of said cabinet and operatively associated with both said piano and said sound reproducing apparatus, said loudspeaker including a diaphragm adapted to directively radiate high frequency sounds near the top of said cabinet, said cabinet having an opening therein in another part thereof, means coupling the back of said diaphragm to said opening and providing an acoustic passage for conducting from said diaphragm to said opening low frequency sounds radiated by said diaphragm, and means for altering the direction of radiation of said high frequency sounds.

EDWARD W. KELLOGG.
